Samuel C. Lawson,
Inventor

By his Attorneys
Macdonald & Macdonald

UNITED STATES PATENT OFFICE.

SAMUEL C. LAWSON, OF CROTON-ON-HUDSON, NEW YORK.

FLUSH TANK.

Application filed March 31, 1920. Serial No. 370,129.

To all whom it may concern:

Be it known that I, SAMUEL C. LAWSON, a citizen of the United States, residing at Croton-on-Hudson, in the county of Westchester and State of New York, have invented certain new and useful Improvements in Flush Tanks; and I do hereby declare that the following is a full, clear, and exact description of the same, reference being had to the accompanying drawings, forming a part of this description, in which similar characters of reference indicate corresponding parts in all the views.

The object of this invention is to provide a siphon valve for use in connection with flush-tanks which shall consist of a minimum number of parts and, at the same time have a maximum efficiency in operation. Further objects of the invention are durability of the same and quietness of operation.

Fig. 1 is a sectional elevation of one form of my improved flushing apparatus; Fig. 2 is a section on the line 2—2 of Fig. 1.

As illustrated in the drawings, the flushing apparatus comprises a tank A, of any approved construction, the inlet thereto not being herein shown. Within the tank and extending downwardly is the outlet pipe B, there being a portion B' leading to the bowl or other place to which water is to be supplied, and an upper portion B², extending upwardly into the tank and surrounded by a circular shell C. This shell is made stationary relatively to the tank. It is open at its lower end and closed at its upper end, where it has a circular depression, C', concentric with the upper end of the outlet pipe B. The purpose of the depression C' in the shell C is to direct the flow of water into the outlet pipe B, as will hereinafter more fully appear. The shell is also provided with ports C². Surrounding the upper pipe B² and movable thereon is a sleeve D, widening at its upper end into a cup D'. To the lower end of the sleeve D are rigidly connected two radially extending arms E, having vertical movement with the sleeve D in the slots F. In the outer ends

of the arms E are perforations E' for connection with bail G, which latter is connected to the usual mechanism H for raising and lowering the valve whenever it is desired to flush the bowl or other place to which it may be connected.

The full lines of the interior cup D' and bail G in Fig. 1 show the same in normal position. When moved into operation by the lifting mechanism H, those parts assume the positions shown in dotted lines. The effect of raising the interior cup D' is to lift the water within and to fill the upper portion of the circular shell C and to start a flow down the pipe B, being assisted over the top of the pipe B by the concentric depression C' in the shell C. A siphoning operation is hereupon established, and continues until broken by the water in the tank being lowered beneath the top of the ports C'.

What I claim is:

1. A flushing apparatus comprising a supply tank, a stand-pipe extending into said tank, a stationary air-chamber surrounding the upper portion of said stand-pipe and having water inlets adjacent to its lower end, and provided, on opposite sides, with slots, a sleeve surrounding the outlet pipe and tapering outwardly therefrom to form a cup and means extending through said slots for operating said sleeve and cup for lifting the water within the casing and causing a siphoning flow from the outlet pipe.

2. A flushing apparatus comprising a supply tank, a stand-pipe extending into said tank, a stationary air-chamber surrounding the upper portion of said stand-pipe and having water inlets adjacent to its lower end, and provided, on opposite sides, with slots, a sleeve surrounding the outlet pipe and tapering on its upper end outwardly therefrom to form a cup and means extending through said slots for operating said sleeve and cup for lifting the water within the casing and causing a siphoning flow from the outlet pipe.

SAMUEL C. LAWSON.
